IRONING MACHINE

John A. Castricone, Peoria, Ill., assignor to Alter-
fer Brothers Company, Peoria, Ill., a corporation
of Illinois

Application July 17, 1937, Serial No. 154,275

9 Claims. (Cl. 38—38)

This invention pertains to ironing machines for both domestic and commercial use and is illustrated as applied to an ironing machine having a transversely curved non-rotating bed commonly known as a flat-bed ironer, but as will become apparent hereinafter, certain features of the invention may be utilized in ironing machines of the rotary or roll bed type and in other types.

One of the primary objects of the invention is to provide an ironing machine in which one of the ironing members may be given a rocking or back and forth ironing movement of a character very similar to that movement utilized by a person in operating a flat or sad iron whereby, for instance, a piece of cloth or material may be pressed in place, that is, without passing it through the ironer or between the ironing members several times as in the case of the ordinary roll-type ironer mechanism. In the embodiment illustrated, an ironing bed having a surface of transversely and convexly arcuate form and conforming generally to the shape of an iron or ironing shoe, is arranged to be rocked back and forth on a horizontal axis to effect the motion specified and for the purposes mentioned.

Another object is to provide an arrangement whereby an ironing machine of the roll bed type may be converted to a flat bed type and vice versa in a simple and inexpensive manner.

Still another important object is to provide a mechanism by which a rocking or back-and-forth motion may be transmitted from a source of motor power through the bed support to the ironing bed.

Many other objects, the advantages and use of the invention will be or should become apparent after reading the following description and claims and after viewing the drawings, in which:

Fig. 1 is a front elevation, with a portion broken away, of an ironing machine embodying a preferred form of the invention;

Fig. 2 is an elevational view of the right hand end of Fig. 1;

Fig. 3 is a front elevational view, partially in section, of the top portion of the ironing machine illustrated in Fig. 1, but on a larger scale;

Fig. 4 is an end elevation of the left hand end of the ironing bed and ironing shoe shown in Fig. 1, but on a scale larger than the scale of Fig. 3;

Figs. 5 and 6 are, respectively, fragmentary sectional views taken along the lines V—V and VI—VI of Fig. 4; the view corresponding like-

wise to the section lines V—V and VI—VI, respectively, in Figs. 6 and 5;

Fig. 7 is an end elevational view of the right hand end of the ironing bed and shoe shown in Fig. 1, showing power transmitting means for operation of the bed and shoe;

Fig. 8 is a large scale plan view of the bed and shoe operating mechanism taken substantially along the line VIII—VIII of Fig. 7;

Fig. 9 is a section taken substantially along the line IX—IX of Fig. 8;

Fig. 10 is a detail plan view of a part of the mechanism for controlling the operation of the ironing shoe and the ironing bed;

Fig. 11 is a detail view taken substantially along the line XI—XI of Fig. 10;

Fig. 12 is a fragmentary view of a portion of the machine showing a part of the mechanism for controlling the operation of the ironing shoe;

Fig. 13 is a fragmentary sectional view of an emergency release mechanism for the ironing shoe taken along section line XIII—XIII of Fig. 14; and

Fig. 14 is a sectional view taken substantially along the line XIV—XIV of Fig. 13.

The machine in general

This application is a continuation in part of applicant's Patent No. 2,115,941, issued May 3, 1938, and the ironing machine illustrated includes various features described and claimed therein. In general the ironing machine comprises an ironing bed 2 supported by standard or frame 3 from a cabinet 4, an ironing shoe 5 supported upon a standard 6 from the cabinet 4, power mechanism including a motor 7 and transmission in a casing or housing generally indicated at 8 (Figs. 1 and 2), and suitable control members 9 and 11. The motor 7 and the transmission and control mechanism are all suitably housed within the cabinet 4. While there are control switches for the motor itself for the heating elements which may be assumed to be carried in the ironing shoe 5, neither such switches nor the elements have been illustrated since they are well known in the art.

The ironing bed

The ironing bed 2 may be constructed per se in any manner well known in the art and to such end may be composed of a sheet metal base plate or frame member 12 carrying padding 13 and covered by an asbestos or other cloth surface covering 14. The metal base plate 12 is transversely curved in the illustrated embodiment on an arc

having a radius greater than the distance from the axis of the rock shaft upon which the bed is mounted to the bed, measured along a perpendicular passing through the center of the cord of that arc and through the axis of said rock shaft. The bed surface is practically straight in a direction at right angles to said arc, that is, may be said to be of the shape of a portion of a cylinder.

The bed is designed to be rocked back and forth, that is, toward and from an observer viewing Fig. 1, and to such end is mounted upon a pair of arms 15 formed upon a hub 16 which is mounted for rocking movements upon a stationary sleeve 17 which is secured in and supported by a boss 18 formed integral with the standard 3. An arm 19, in the outer end of which a fulcrum pin 21 is secured, has a hub portion 22 surrounding the sleeve 17 and is adjustably secured thereto by a set screw 23, while a hardened washer 24 serves as a bearing member between the hub 16 and the hub 22.

One of the arms 15 is provided with an offset portion 25 in which a stud 26 is fixed and pivotally mounted upon the stud 26 is a rocker member 27, the opposite ends of which are slotted with open ended slots 28 and 29, slot 28 receiving the end of stud 21 and slot 29 receiving a crank pin 31 which is firmly secured in a plate 32. The rocker member 27 is held upon the pivot pin 26 by a washer 33 in turn held in place by cotter key or the like 34. Plate 32 is held to a rock shaft 35 by a stud screw 36, but is prevented from rotation with respect to the shaft 35 by lugs 37 formed on a bearing member 38 pinned by a pin 39 to the shaft 35, the plate 32 being provided with apertures 41 for the reception of the lugs 37. A guard and housing member 42 may surround the sleeve 17 between the hub 22 of arm 19 and the standard 3.

The rock shaft 35 finds bearing within the sleeve 17 through the bearing member 38 at the one end and through a bearing member 43 at the other end but projects out of the sleeve 17 beyond the bearing member 43 where it carries a sprocket 44 rigidly secured thereto for driving engagement by a chain 45 whereby the shaft may be rocked or rotated as will hereinafter appear. It will be noted from the mechanism so far described that if the shaft 35 be rocked through a reasonable angle of say 30° (15° clock-wise and 15° counter-clock-wise) from the position represented in Fig. 4, a corresponding rocking movement will be imparted to the plate 32 and to the rock member 21, which being in effect fulcrumed upon the pin 21, will cause the arms 15 and the ironing bed to rock through a corresponding angle on the sleeve 17. However, the angle through which the bed 2 rocks will be a lesser angle than the angle through which the shaft 35 has been moved. In other words, the rocking mechanism described provides, in effect, a reduction gear between the rock shaft 35 and the ironing bed.

Transmission mechanism for applying power to the bed rock shaft

The arrangement is such that the shaft 35 may be rocked for the purpose of rocking a flat bed, such as that illustrated, or rotated or rocked for the purpose of rotating or rocking a roll type bed, such as that illustrated and described in the above noted co-pending application. The substitution of a roll type of bed for the flat bed shown may be accomplished merely by removing the flat ironing bed together with the arms 15 and 19 and the plate 32 and sub-

stituting an ironing roll, such for instance as that illustrated and described in my aforesaid co-pending application. Consequently, the mechanism herein disclosed for driving the shaft 35 may be operated to rock the shaft 35 for a flat bed ironer or for rotating the shaft or for rocking it when a roll ironing bed is used. This operating mechanism will now be described.

Mounted in suitable bearing in the standard 3 is a short shaft 46 on which a pair of sprockets 47 and 48 are secured, the sprocket 47 driving the chain 45 and the sprocket 48 being driven by a chain 49 in turn driven by a sprocket 51 fixed to a shaft 52 as with a set screw 53. The shaft 52 is supported at one end in a bushing 54 carried by a bracket 55 carried by the casing 8 and at its other end is reduced and carries a bushing 56 upon which a pinion 57 is mounted and which in turn is surrounded at one end by a bushing 58 secured in a boss 59 in the casing or housing 8. The reduced end of the shaft 52 is adapted to rotate freely under certain circumstances with respect to the pinion 57, and the pinion 57 is adapted to rotate within the bushing 58.

Intermediate the bushing 54 and the pinion 57 an enlarged portion 61 on the shaft 52 is splined to a circumferentially slotted clutch collar 62 which may be shifted in one direction longitudinally of the shaft 52 to engage projection 63 carried thereon with projections 64 carried by the pinion 57 or in the other direction to engage projections 65 with pins 66 carried by a pinion 67 freely mounted upon the shaft 52 between the enlarged portion 61 and a thrust collar 68 pinned to the shaft 52. It will be apparent that movement of the clutch collar 62 in one direction will connect the pinion 57 with the shaft 52 and in the opposite direction will engage the pinion 67 with the shaft 52. While I have illustrated and described a mechanism for shifting the clutch collar 62, in my said co-pending application, any other mechanism well known in the art for shifting the same may be utilized, and for such reason no means is particularly disclosed herein. It may be assumed, for the purpose of illustration of the invention, that the clutch collar 62 is connecting pinion 57 with the shaft 52 at all times and is only to be connected with the pinion 67 when the shaft 35 is to be rotated and not rocked.

Rocking movement is imparted to the shaft 52 by a sector gear 69 formed upon one end of a rocker 71 pivotally mounted upon a stub shaft 72 between a bearing washer 73 and a pinion 74 also freely mounted for rotation upon shaft 72 and retained in place thereon by bearing washer 75 in turn held in place by a cotter pin or the like 76, the shaft 72 being firmly secured in a boss 71 formed in the casing or housing 8. The other arm 78 of the rocker 71 carries a pivot pin 79 upon which an arm 81, forming a part of an eccentric strap member 82, is pivotally secured, the strap being engaged about an eccentric or cam 83 formed integral with a pinion 84 rotatably mounted upon a shaft 85 secured in a boss 86 in the casing or housing 8. Hardened thrust washers 87 and 88 serve to take up any end thrust of the eccentric 83 and pinion 84. The pinion 84 is at all times meshed with a gear 89, and the gear 89 also meshes with a pinion 91 carried on the stub shaft 72 and which in turn is meshed at all times with the pinion 67. It will thus be apparent that if the gear 89 be driven in either direction, rocking motion may be imparted to the shaft 52 through the gear 84, eccentric strap 82, rocker 71, sector gear 69, pin-

ion 57 and the clutch collar 62, or rotary movement may be imparted to the shaft 52 through the engagement of gear 89 with pinion 91, pinion 67 and clutch collar 62.

The gear 89 is rotatably mounted upon a shaft 92, and integrally formed with the gear is a toothed clutch member 93 between which and the gear is a slot 94 within which the forked arms of a clutch shifter 95 are engaged and adapted to ride. The gear 89 is made wide enough so that it may be shifted longitudinally on the shaft 92 to engage the clutch teeth of the clutch member 93 with cooperative teeth 96 formed on a worm gear 97, the while remaining in constant engagement with gears 84 and 91. The worm gear 97 is rotatably mounted upon the shaft 92 and is driven by a worm 98 fixed to a shaft 99 connected with the electric motor or other power device indicated at 7. When the teeth of clutch member 93 are engaged with teeth 96 when the motor is operating, the gear 89 is driven and shaft 52 will be driven through the chains of gears heretofore described, either continuously in one direction or back and forth through a predetermined number of degrees.

Power applying mechanism for ironing bed shaft and ironing shoe rock shaft

Rotatably mounted on the shaft 92 is an element 101 which is arranged to be rotated between the position in which it is illustrated in Figs. 8 and 10, and a position of 180° removed therefrom. The inner end of element 101 is provided with two transverse slots 102 and 103 (see Fig. 11) which are substantially at right angles to one another. Within the slot 102 and pivotally mounted upon a reduced portion 104 of the member 101 is a member 105 having oppositely directed fingers 106 and carrying a pin 107. Normally, member 105 is urged in a counter-clockwise direction (viewing Fig. 11) about the portion 104 by a tension spring 108 fixed between a post 109 secured to member 101 and a pin 111 attached to one of the fingers 106. Within the slot 103 and longitudinally slideable therein is a plate 112 which is slotted as at 113 to receive the pin 107, which has an elliptical slot 114 through which the shaft 92, and the portion 104 freely pass, and to which a plate 115 having a projection or tooth 116 is rigidly secured at one end. Cap screws or screws and washers 117 plus the post 109 and washer 118, secured to the member 101 serve to retain the plate 112 within the slot 103 for sliding movements therein. The projection or tooth 116 is adapted to be received in any one of a series of depressions or notches 119 formed in a disk 121 rigidly secured to the worm gear 97 for rotation therewith.

Normally in the position shown in Fig. 11 where it serves to engage one of the fingers 106, is a dog 122 formed on a lever 123 pivoted upon a pivot pin 124. This dog 122 may be released from a finger 106 when the lever 123 is moved about its pivot in the direction of the arrow shown thereon in Fig. 11 whereupon spring 108 will swing the member 105 about its pivot to the opposite side of a slot 102 from the position in which it is shown in Fig. 11, thereby causing the pin 107 to move the slide plate 112 to the left, thereby engaging the tooth 116 in one of the recesses 119 in the disk 121, and element 101 will proceed to rotate with worm gear 97 if this gear is being rotated.

The lever 123 is arranged to be operated through certain connections including a pull rod 125, a crank arm 126 secured on one end of a

pivot pin 127 rotatably mounted in a boss 128 formed on the housing 8, a crank arm 129 secured on the opposite end of pivot pin 127, a pull rod 130, and lever control member 9 pivoted 5 within the cabinet 4 on a pivot 131 and pivotally connected to the pull rod 130 on a pivot 132. In order to limit the movement of cranks 126 and 129 and thus the extent of movement of lever 123, the crank 129 is continued beyond the 10 pivot 127 where it is forked to provide projections 133 both of which are arranged to engage a pin 134 secured to the frame of the machine. The lever 9 is arranged to be operated by the 15 knee of the machine operator. It is intended that the lever 9 shall be pushed or nudged by the operator only momentarily and only long enough to release the dog 122 from behind the tooth 106 whereupon the control will be immediately released so that the dog 122 is free to engage behind a succeeding finger 106 to which position the dog is returned immediately by the 20 action of a tension spring 135 which may be secured between the pull rod 125 and a portion of the bracket 55. Thus, when the element 101 has rotated 180°, the succeeding finger 106 will engage the dog, and, through the medium of the pin 107 engaged with the walls of the slot 105, will move the tooth 116 out of engagement with the disc 121 and the element 101 will come to rest.

The outer end of element 101 is formed with an eccentric 136 about which an eccentric strap 137 is secured. At the high point of the eccentric and inwardly therefrom, a cam surface 138 is formed, the purpose of which will shortly appear. 30 The eccentric strap 137 may be formed integrally with a housing 139 which contains a spring 141, one end of which is arranged to abut against tongues 142 struck from the housing 139. A rivet 143 may serve to hold the housing sides in position as well as to retain the end of the spring 141 in its position. The opposite end of spring 141 bears against a pin 144 rigidly secured through and to the arms 145 of a forked crank member 146 fixedly secured to a rock shaft 147 35 rotatably mounted in bearing 148 carried by a boss 149 in the housing 8. The rock shaft 147 projects outwardly of the housing 8 where it is pinned by a pin 151 in a collar 152 integral with a crank arm 153. A hardened plate 154 also surrounds this end of the rock shaft 147 and is secured to the crank arm 153 by a bolt 155. The rock shaft 147 is extended even beyond the plate 154 where it enters a guide bushing member 156 securely pinned by a pin 157 to a shaft 158. The guide bushing member 156 is provided with an integral projecting portion 159 within which a plunger 161 is reciprocally mounted and normally urged toward the left (viewing Fig. 13) by a spring 162 which abuts 40 at one end against a shoulder formed on the plunger 161 and a shoulder provided by a gland nut 163 screwed into the projecting portion 159 but through which the plunger 161 is adapted to be slid. The hardened plate 154 is provided with an aperture adapted snugly but slidably to receive the tapered end of plunger 161 and when the plunger is entered into this aperture the shaft 158 is rigidly connected with the rock shaft 147 to be rocked thereby.

45 It will be apparent that when the operator releases the dog 122 from one of the fingers 106 and the element has rotated through 180° the element will, in one position, come to rest as shown in Fig. 8, where the spring 141 will have been compressed and will have urged the pin 50

144 toward the extreme right. The forked crank member 146 and the rock shaft 147 will have been rocked to the position shown in Figs. 7 and 8, but, depending upon the extent to which the rock shaft 147 may be moved (this movement is determined by several factors although chiefly by the contact of an iron with a roll or bed member as will be appreciated) the pin 144 may ride back in slots 140 formed in the housing 139, while the spring 141 compresses. Upon the operator's next release of the dog 122 the element 101 will again rotate 180° at which time the tension upon the spring 141 will be released and the forked crank member 145 and the rock shaft 147 will be urged in a clockwise direction (viewing Fig. 7) and at this time the cam surface 138 will have engaged a projecting arm 164 secured between a flange 165 and a sleeve 166 carried by a plunger 167 slidably held in a boss 168 on housing 8 and urged outwardly of the boss by a spring 169. Held between a nut 171 the sleeve 166 is the forked clutch control member 95, so when the cam surface 138 strikes the arm 164 it forces the plunger 167 into the recess of the boss 168, compresses spring 169 and, simultaneously, through the forked clutch control member 95, disengages the clutch elements 93 and 96.

The main ironing shoe and its operating mechanism

The standard 6 supports an ironing shoe through a support member 172 which is pivoted to the standard on a horizontal pivot 173. The ironing shoe 5 carries a pair of lugs 174 which are disposed on either side of an arm 175 and through which an arm 176, a horizontal pivot 176 extends. Springs 177 permit limited and resilient oscillation of the shoe about the pivot 176. The arm 175 has a bearing boss 178 disposed over a pivot 179 which is secured in a boss 181 on the member 172 as by a pin 182. Thus, the shoe 5 may rock about the pivot 176 and may be moved longitudinally of the bed 2 to a certain extent in each direction about the pivot 179.

The ironing shoe support 172 is arranged to be rocked about the pivot 173 to carry the ironing shoe toward or away from the ironing bed 2, by a curved operating rod 183 which at its upper end is pivotally secured as at 184 to the support 172 and at its lower end is pivotally connected as at 185 to a crank 186 secured on the end of rock shaft 158. At this end the rock shaft passes through a lug 187 formed on the standard 6 and is held in position by fixed collar 188. A tension spring 189 connected between the pivot 173 and a post 191 normally tends to pull the rod 183 upwardly and to swing the ironing shoe 5 away from the bed 2. It will be apparent that when the forked arms 145 are moved in a counter-clockwise direction to rock the rock shaft 147 in the same direction, the curved rod 183 will be pulled down and will move the ironing shoe 5 against the bed 2.

The plunger 161 normally maintains the rock shafts 147 and 158 in cooperative association, but in case the power should fail while the iron is being pressed against the bed, mechanism is provided whereby the operator may substantially instantaneously disconnect the rock shaft 147 from rock shaft 158 so that the ironing shoe may be thrown back away from the bed manually. The disconnecting mechanism includes a pull rod 192 pivotally connected as at 193 with

the plunger 161 at one end and pivotally connected by a bolt 194 at its other end with an arm 195 carried by a crank 196 fixed to a shaft 197 which has bearing in suitable bearings provided in the cabinet housing and which at the front of the cabinet is connected with the control handle 11. By movement of the handle 11 the plunger 161 may be released from the hardened plate 154 whereupon the ironing shoe 5 may be swung about its pivot 173 away from the ironing bed.

Operation of machine

Assuming that the switch controlling the motor (switch not shown) has been closed to start the motor 7, the worm 98 will drive the worm gear 97 continuously. As soon as the operator is ready to iron, a nudge of the knee against the control lever 9 will move the dog 122 out of the path of one of the fingers 106 which will permit the spring 108 to shift the member 105 so as to move the dog 116 into one of the notches 119 thereby to rotate the member 101 through 180° or until the dog 122 intercepts the next finger 106. The cam 136 will move 180° to the position illustrated in Fig. 10, at which time the iron 5 will be urged downwardly under resilient pressure against the bed 2. As the cam surface 138 on the member 101 moves away from the arm 164 the spring 169 will move the forked member 95 to slide the gear 89 on shaft 92 to cause the clutch members 93 and 96 to engage with one another and if the clutch collar 62 is engaged with the pinion 57 (through operation of a manual control not shown) the shaft 52 will be rocked and through the mechanism previously described will rock the bed back and forth toward and from the operator. Inasmuch as the ironing shoe is mounted for movement about its horizontal pivot 176, it will partake to a certain extent of the rocking movements of the bed, but owing to the disposition of its pivot 176 with respect to the pivot mounting of the bed a differential or relative sliding movement will take place between the bed and ironing shoe of a character closely simulating the motion of a hand iron over the bed. A certain amount of oscillatory movement longitudinal of the bed may be imparted to the iron by reason of its mounting upon the pivot 179.

While I have illustrated and described a preferred embodiment of the invention and preferred types of mechanism in that embodiment, it will be apparent that many modifications may be effected and that various other arrangements may be devised without departing from the spirit of the invention and the scope of the appended claims.

I claim:

1. In an ironing machine, a support, a sleeve rigidly secured by one of its ends to said support, the other end of said sleeve being unsupported, a shaft rotatably supported in said sleeve, an arm secured to and projecting transversely of the axis of said sleeve adjacent to said other end, an ironing bed supporting member mounted on said sleeve between said arm and the adjacent end of said sleeve, a rocker arm pivotally secured intermediate its ends to said bed supporting member at a place spaced from said sleeve and upon an axis substantially parallel to the axis of said shaft, means on said arm providing a fixed pivot for one end of said rocker arm, said end of said rocker arm being pivoted upon said fixed pivot, a crank arm secured to said shaft and

operatively associated with the other end of said rocker arm, and means for rocking said shaft.

2. In an ironing machine the combination of a non-rotating and non-cylindrical arcuate bed adapted to support material to be pressed, an arcuate ironing shoe, supports for said arcuate bed and for said ironing shoe, shifting means for said supports whereby said bed and shoe may be relatively moved between an operating position wherein their surfaces are urged into pressing engagement with each other, and an inoperative position wherein said bed and shoe are moved into spaced relationship with each other; power-operated pressure engaging means including a motor and reduction gear train whereby said bed and shoe may be successively engaged and disengaged; power-operated means for imparting substantially continuous differential sliding movement between said bed and shoe while said bed and shoe are maintained in aforementioned pressure engagement; and control means for simultaneously operating said pressure engaging means and said differential sliding movement means.

3. In an ironing machine the combination of a non-rotating and non-cylindrical arcuate bed adapted to support material to be pressed, an arcuate ironing shoe, supports for said arcuate bed and for said ironing shoe, shifting means for said supports whereby said bed and shoe may be relatively moved between an operating position wherein their surfaces are urged into pressing engagement with each other, and an inoperative position wherein said bed and shoe are moved into spaced relationship with each other; power-operated pressure engaging means including a motor and reduction gear train whereby said bed and shoe may be successively engaged and disengaged; and power-operated means for imparting substantially continuous differential sliding movement between said bed and shoe while said bed and shoe are maintained in aforementioned pressure engagement.

4. In an ironing machine, the combination of a pair of cooperating ironing elements comprising a non-rotating and non-cylindrical bed adapted to support material to be pressed, and a cooperating ironing shoe; supports for said ironing elements, shifting means for said supports whereby said bed and shoe may be relatively moved between an operating position wherein their surfaces are urged into pressing engagement with each other and an inoperative position wherein said bed and shoe are moved into spaced relationship with each other; power-operated pressure engaging means including a motor and reduction gear train whereby said bed and shoe may be caused to engage or disengage; pivotal mounting means for one of said ironing elements adapted to permit limited rocking movement of said element, power-operated oscillating means including an eccentric for imparting said rocking movement to said ironing element; pivotal mounting means for the other of said ironing elements adapted to permit limited rocking movement of said element whereby said element may be free to follow the angular positions assumed by the driven element to maintain their cooperating surfaces in constant pressure engagement substantially throughout their area.

5. In an ironing machine, the combination of a pair of cooperating ironing elements comprising a non-rotating and non-cylindrical bed adapted to support material to be pressed, and a cooperating ironing shoe; supports for said

ironing elements, shifting means for said supports whereby said bed and shoe may be relatively moved between an operating position wherein their surfaces are urged into pressing engagement with each other and an inoperative position wherein said bed and shoe are moved into spaced relationship with each other; power-operated pressure engaging means including a motor and reduction gear train whereby said bed and shoe may be caused to engage or disengage; pivotal mounting means for one of said ironing elements adapted to permit limited rocking movement of said element; power-operated oscillating means including an eccentric for imparting said rocking movement to said ironing element; pivotal mounting means for the other of said ironing elements, said pivotal mountings of said bed and shoe being on different centers and being so arranged as to anchor the ironing bed and shoe in such relative positions that the aforementioned rocking movement will be effective to maintain constant differential sliding movement between said bed and shoe.

6. In an ironing machine, the combination of a pair of cooperating ironing elements comprising a non-rotating and non-cylindrical arcuate bed adapted to support material to be pressed, and an arcuate ironing shoe; supports for said ironing elements, shifting means for said supports whereby said bed and shoe may be relatively moved between an operating position wherein their surfaces are urged into pressing engagement with each other and an inoperative position wherein said bed and shoe are moved into spaced relationship with each other; engaging means whereby said bed and shoe may be caused to engage or disengage; pivotal mounting means for one of said ironing elements adapted to permit limited rocking movement of said element about a center not concentric with the arcuate surface of the said ironing element; power-operated oscillating means for imparting said rocking movement to said ironing element; pivotal mounting means for the other of said ironing elements adapted to permit limited rocking movement of said element about a center not concentric with the ironing surface of said ironing element whereby said element may be free to follow the angular positions assumed by the driven element to maintain their cooperating arcuate surfaces in constant pressure engagement substantially throughout their area.

7. In an ironing machine, the combination of a pair of cooperating ironing elements comprising a non-rotating and non-cylindrical arcuate bed adapted to support material to be pressed, and an arcuate ironing shoe; supports for said ironing elements, shifting means for said supports whereby said bed and shoe may be relatively moved between an operating position wherein their surfaces are urged into pressing engagement with each other and an inoperative position wherein said bed and shoe are moved into spaced relationship with each other; engaging means whereby said bed and shoe may be caused to engage or disengage; pivotal mounting means for one of said ironing elements adapted to permit limited rocking movement of said element about a center not concentric with the arcuate surface of the said ironing element; power-operated oscillating means for imparting said rocking movement to said ironing element; pivotal mounting means for the other of said ironing elements, said pivotal mountings of said bed and shoe being on different centers and be-

ing so arranged as to anchor the ironing bed and shoe in such relative positions that the aforementioned rocking movement will be effective to maintain constant differential sliding movement between said bed and shoe.

8. In an ironing machine, the combination of a pair of cooperating ironing elements comprising a non-rotating and non-cylindrical arcuate bed adapted to support material to be pressed, and an arcuate ironing shoe; supports for said ironing elements, shifting means for said supports whereby said bed and shoe may be relatively moved between an operating position wherein their surfaces are urged into pressing engagement with each other and an inoperative position wherein said bed and shoe are moved into spaced relationship with each other; power-operated pressure engaging means including a motor and reduction gear train whereby said bed and shoe may be caused to engage or disengage; pivotal mounting means for said ironing bed adapted to permit limited rocking movement of said bed about a center not concentric with the arcuate surface of the said bed; power-operated oscillating means including an eccentric for imparting said rocking movement to said ironing bed; pivotal mounting means for said ironing shoe adapted to permit limited rocking movement of said shoe about a center not concentric with the ironing surface of said shoe whereby said shoe may be free to follow the angular positions assumed by the ironing bed to

maintain their cooperating arcuate surfaces in constant pressure engagement.

9. In an ironing machine, the combination of a pair of cooperating ironing elements comprising a non-rotating and non-cylindrical arcuate bed adapted to support material to be pressed, and an arcuate ironing shoe; supports for said ironing elements, shifting means for said supports whereby said bed and shoe may be relatively moved between an operating position wherein their surfaces are urged into pressing engagement with each other and an inoperative position wherein said bed and shoe are moved into spaced relationship with each other; power-operated pressure engaging means including a motor and reduction gear train whereby said bed and shoe may be caused to engage or disengage; pivotal mounting means for said ironing bed adapted to permit limited rocking movement of said bed about a center not concentric with the arcuate surface of the said bed; power-operated oscillating means including an eccentric for imparting said rocking movement to said ironing bed; pivotal mounting means for said ironing elements, said pivotal mountings of said bed and shoe being on different centers and being so arranged as to anchor the ironing bed and shoe in such relative positions that the aforementioned rocking movement will be effective to maintain constant differential sliding movement between said bed and shoe.
